A. RASMUSSEN

WRINGER

Filed Nov. 20, 1924

Inventor

A. Rasmussen

By Watson E. Coleman
Attorney

UNITED STATES PATENT OFFICE.

ALFRED RASMUSSEN, OF ST. PAUL, MINNESOTA.

WRINGER.

Application filed November 20, 1924. Serial No. 751,082.

To all whom it may concern:

Be it known that I, ALFRED RASMUSSEN, a citizen of the United States, residing at St. Paul, in the county of Ramsey and State 5 of Minnesota, have invented certain new and useful Improvements in Wringers, of which the following is a specification, reference being had to the accompanying drawings.

This invention relates to certain improvements in wringers and has relation more particularly to a structure of this kind particularly adapted for use in connection with mops and it is an object of the invention to provide a device of this general character 15 embodying novel and improved means whereby sufficient pressure may be imposed upon the mop to free the same of moisture carried thereby.

Another object of the invention is to provide a novel and improved device of this general character especially designed and adapted for use in connection with a mop embodying the solid back together with a working face of absorbent material, such as 25 felt or the like.

The invention consists in the details of construction and in the combination and arrangement of the several parts of my improved wringer whereby certain important 30 advantages are attained and the device rendered simpler, less expensive and otherwise more convenient and advantageous for use, as will be hereinafter more fully set forth.

The novel features of my invention will 35 hereinafter be definitely claimed.

In order that my invention may be the better understood, I will now proceed to describe the same with reference to the accompanying drawings, wherein:—

40 Figure 1 is a view in perspective of a wringer constructed in accordance with an embodiment of my invention the operating handle being broken away;

Figure 2 is a side elevational view of my 45 improved wringer as herein disclosed, the applied mop being diagrammatically indicated by broken lines;

Figure 3 is a view in top plan of the structure as illustrated in Figure 2 with the 50 applied mop indicated by broken lines;

Figure 4 is a view in end elevation of the structure as illustrated in Figure 2, a portion being broken away and the applied mop being also diagrammatically indicated.

55 As disclosed in the accompanying drawings, 1 denotes an elongated base member 1

preferably rectangular in form and comprising any suitable material. Extending transversely of the base member 1 at substantially its longitudinal center is a U-shaped member 60 2 the intermediate base or face portion 3 of which underlying the base member 1 and suitably secured thereto, as at 4.

The side members 5 of the member 2 extend a desired distance above the base member 1 and snugly fitting between the upper or free end portions of the side members 5 is a block 6 having its upper side marginal portion pivotally engaged with the bolt 7 freely extending therethrough and also 70 through the free end portions of the side members 5. The opposite side face of the block is rounded, as at 8. Extending substantially at right angles from the outer side marginal portion of the block 6 is an operating handle 9.

In the present embodiment of my invention, I illustrate my improved wringer for use in connection with the mop diagrammatically indicated by broken lines which 80 consists of a back 10 having overlying one face thereof a working member 11 of felt or kindred material. However, in practice I do not wish to be understood as limiting my wringer to a mop of this kind. 85

The block 6 constitutes a cam member and when a mop is positioned upon the base member 1, the handle member 9 is forced downwardly swinging the rounded side face 8 of the block 6 into contact with the back 10 90 resulting in sufficient pressure being imposed upon the working face 11 of the mop to force therefrom all moisture therein.

The block 6 at substantially its longitudinal center has disposed transversely therethrough a groove 12 to facilitate the application of the mop in desired position and particularly to permit a passage therethrough of the conventional nut carried by the mop. 95

The upper face of the base member 1 also 100 has disposed therealong the grooves 14 to facilitate drainage.

In practice, the wringer is preferably disposed over a pan with the base member 1 disposed on a desired incline such incline 105 being effected by the use of a block or the like arranged beneath one end of the member 1.

From the foregoing description it is thought to be obvious that a wringer constructed in accordance with my invention is 110 particularly well adapted for use by reason

of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as herein-after claimed.

I claim:

1. A wringer of the class described comprising a base member, upstanding arms carried thereby and spaced transversely thereof, a block interposed between said arms and above the base member, means eccentric to the axial center of the block supporting said block by the arms for rocking movement, and means for rocking the block, said block constituting a cam member to exert pressure upon rocking movement of the block upon the article positioned upon the base member and underlying the block.
2. A wringer of the class described comprising a base member, upstanding arms carried thereby and spaced transversely

thereof, a block interposed between said arms and above the base member, means eccentric to the axial center of the block supporting said block by the arms for rocking movement, and an operating handle carried by the block, said block constituting a cam member to exert pressure upon rocking movement of the block upon the article positioned upon the base member and underlying the block.

3. A wringer of the class described comprising a base member, upstanding arms carried thereby and spaced transversely thereof, a block interposed between said arms and above the base member, means eccentric to the axial center of the block supporting said block by the arms for rocking movement, and means for rocking the block, the upper surface of the base member having drainage grooves extending therealong, said block constituting a cam member to exert pressure upon rocking movement of the block upon the article positioned upon the base member and underlying the block.

In testimony whereof I hereunto affix my signature.

ALFRED RASMUSSEN.
